US0D1042569S

(12) **United States Design Patent** (10) **Patent No.:** **US D1,042,569 S**
(45) **Date of Patent:** **** Sep. 17, 2024**

(54) **SOLDERING GUN**

(71) Applicant: **Shenzhen Teke Electronic Equipment Co., Ltd.**, Shenzhen (CN)

(72) Inventor: **Junqiang Li**, Shenzhen (CN)

(**) Term: **15 Years**

(21) Appl. No.: **29/936,607**

(22) Filed: **Apr. 9, 2024**

(30) **Foreign Application Priority Data**

Mar. 15, 2024 (CN) 202430132415.9

(51) **LOC (14) Cl.** **15-09**

(52) **U.S. Cl.**

USPC **D15/144.2**; D8/30

(58) **Field of Classification Search**

USPC D15/144, 144.1, 144.2; D8/30, 29.1, 51, D8/70

(57) **CLAIM**

The ornamental design for a soldering gun, as shown and described.

DESCRIPTION

FIG. 1 is a perspective view of a soldering gun showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof;

FIG. 9 is an enlarged view of portion of FIG. 1;

FIG. 10 is an enlarged view of portion of FIG. 1; and,

FIG. 11 is an enlarged view of portion of FIG. 2.

The evenly-dashed broken lines in the drawings depict portions of the soldering gun that form no part of the claimed design. The dot-dash broken lines in the drawings designating the boundary of the enlarged views form no part of the claimed design.

1 Claim, 11 Drawing Sheets
